UNITED STATES PATENT OFFICE.

JOHANNES RUTHS, OF DJURSHOLM, AND NILS PERSSON, OF BREVIK, LIDINGON, SWEDEN, ASSIGNORS TO AKTIEBOLAGET VAPORACKUMULATOR, OF STOCKHOLM, SWEDEN, A CORPORATION.

STEAM-ACCUMULATOR APPARATUS FOR STEAM PLANTS.

Application filed July 10, 1922. Serial No. 574,089.

To all whom it may concern:

Be it known that we, JOHANNES RUTHS and NILS PERSSON, subjects of the King of Sweden, residing at, respectively, Djursholm, Sweden, and Brevik, Lidingon, Sweden, have invented certain new and useful Improvements in Steam-Accumulator Apparatus for Steam Plants (for which we filed application for patent in Sweden, May 10, 1921), of which the following is a specification.

In steam plants equipped with accumulators it is old to cause the steam to pass through a motor such as a turbine or a reciprocating engine in which power is extracted, after which the steam is led to low pressure consumers if all the steam can be used therein; or, when more steam is supplied than is needed by the low pressure consumers, the surplus is led from the motor to an accumulator to be stored, from which accumulator the steam is withdrawn for use when necessity demands. In such plants, the back pressure or extraction pressure of the motor, that is to say, that pressure to which the steam for the low pressure consumers expands in the motor is either always higher than the highest accumulator pressure or the same as that pressure and variable therewith. In the latter cases where the extraction pressure is substantially the same as and varies with the pressure in the accumulator, it is evident that the amount of power extracted in the motor is a function of the variable pressure in the accumulator.

In some instances, it has been found that it is possible to extract more power from the steam for the low pressure consumers if this steam can expand in the motor from the high pressure of the line from which it is taken all the way down to the pressure at which the low pressure consumers use steam and have this complete expansion irrespective of variations of pressure in the accumulator, and the surplus of steam generated over the momentary consumption is led in a path parallel to the path of steam passing through the motor to the accumulator, from which steam is led to the low pressure consumers when the demand on these consumers is greater than the supply afforded by the motor.

The present invention has for its purpose to provide means whereby the greater ex-

traction of power in the motor as above outlined is accomplished and comprises an arrangement including one or more steam generators; a steam conduit system connected therewith; a steam accumulator, a motor, and one or more low pressure consumers connected in said conduit system; in combination with means to carry out the purpose set forth, involving a conduit leading steam from the accumulator to the low pressure consumers, a reducing valve or the equivalent in this conduit and means whereby steam extracted from the motor is led to this conduit at a point behind the reducing valve, that is, between the reducing valve and the low pressure consumers, and also involving certain regulating mechanisms necessary to the best realization of the invention, the function and advantages of which will be apparent as the description proceeds.

In the accompanying drawings which are a part of this specification:

Fig. 1 is a diagram showing typical curves of steam consumption and generation in a plant in accordance with this invention, the curves being arranged in a special way, as will hereinafter be described.

Fig. 2 is an arrangement of a plant in accordance with the present invention and shows the manner of connecting the accumulator and the steam generator to the low pressure line.

Fig. 3 shows a plant in accordance with the present invention wherein certain pressure operated regulating mechanisms are used, which are more fully explained hereinafter.

Fig. 4 is another plant having a different means of regulation.

Fig. 5 is another plant showing still another form of regulation.

Fig. 6 is an arrangement including a single extraction turbine.

Fig. 7 is an arrangement similar to Fig. 6 with a different form of regulation.

Fig. 8 is an arrangement using a double extraction turbine.

Fig. 9 is a regulating arrangement in detail.

To best understand the invention the various elements and characters shown on the drawings will first be explained in a general way, particular reference being had to Fig.

2. In the various figures of the drawings like characters represent like parts. A represents the boilers in which steam is generated. B is a conduit connected to the boilers for receiving steam therefrom at boiler pressure. C is a steam motor, in the illustration a non-condensing, back pressure turbine, receiving steam from the high pressure conduit B. The turbine drives an electric generator D, delivering electric power to the electric circuit E. K and G are parts of a conduit within the plant system which is at lower pressure than the main high pressure conduit B and steam generator A. The conduit K is herein termed an "accumulator conduit". The pressure in this conduit varies with variations of pressure in the accumulator F. G is the conduit from which the low pressure consumers, such as paper machines H are supplied with steam. G is herein termed "low pressure conduit". In conduit K—G between accumulator conduit K and low pressure conduit G is provided a reducing valve J.

25 According to the present invention the back pressure steam passes to the low pressure conduit G at a point after the reducing valve J. By this arrangement it is possible to keep the back pressure independent 30 of the pressure in the accumulator F, and equal to the pressure of the low pressure consumers, although it is lower than the pressure in the accumulator. The valve M in conduit L opens and allows steam to pass 35 to the accumulator F when the pressure in the conduit B rises above a predetermined value.

40 Valves operating in this manner to increase the valve opening when the actuating pressure increases and to decrease the valve opening when the pressure decreases, we term "over-flow" valves.

45 In the conduit N, connecting conduit B with conduit K is a reducing valve O which opens if the pressure which controls it should sink below a predetermined value. This valve operates to allow steam to pass towards the accumulator in certain cases if the accumulator is completely discharged. 50 The small lines connecting the valves with the steam conduits indicate by which pressure the valves are operated.

55 In the operation of the plant according to Fig. 2, steam is generated in steam generator A and passes into conduit B. Here the steam divides itself into two paths, the one through conduit L and through or past the accumulator, through valve J, and thence to the low pressure consumers; the other path being through the supply conduit 55 to the motor C, through the motor C, through the back pressure connection 51 and thence, also, to the low pressure consumers. Thus it is seen that there are two parallel paths of steam leading from generator A to coin-

sumers H, the one having an over-flow valve M and a reducing valve J in it and an accumulator F connected therewith intermediate the over-flow valve and the reducing valve and the other path having a motor in it. In Fig. 2 the power generated in turbine C is all consumed in the circuit E. The number of revolutions of the turbine correspond to the frequency of the circuit and it is only necessary to provide the steam motor with a speed regulator which will come into play only if the motor for some reason or other should speed up too much.

If a uniform steam production is to be obtained and no steam losses are to occur, as 80 is the purpose of accumulator plants of the type herein described, the plant designed according to Fig. 2 is only possible where the consumption of the low-pressure consumers is always greater than the consumption of 85 the high pressure motor, i. e., the turbine C, and this must be the case at any and every moment and, further, where the consumption of the steam motor never exceeds the momentary generation. Steam plants are seldom so simple that they can be arranged in 90 this way. To assure a good working it is usually necessary to regulate the flow of steam to the steam motor by two pressures, and preferably also by the speed of the 95 motor.

To best explain the more involved phases of this invention, a series of curves is shown in Fig. 1 which are taken to represent a plant 100 wherein certain consumers such as digesters receive steam directly from the boilers or from a conduit in the system connected ahead of the motor. A study of these curves will indicate the mode of operation and the necessity in the majority of cases for the pressure operated regulating mechanisms hereinbefore referred to. In this figure the ordinates represent steam quantity and the abscissas represent time.

110 The line a represents the average consumption of the plant which is the same as the amount of steam generated in the boilers. That the boilers can be made to generate this constant average quantity of steam is due to the fact that the accumulator takes 115 care of all variations in steam consumption wherever they occur in the plant and the boilers are relieved of these variations.

120 The steam consumption of the consumers connected directly with the boilers or the high pressure conduit is indicated by curve b, measured upwardly from the horizontal axis of coordinates. This might be called the curve of high pressure steam consumption.

125 The steam consumption of the consumers connected to the low pressure line is laid out in the diagram downwardly from the line a, for reasons apparent as the description proceeds, and is indicated by the line c, refer-

ence being had to the values at the right of Fig. 1. This might be called the curve of low pressure steam consumption.

At a given time d , the amount of steam supplied by the boilers is represented by the ordinate e ; the consumption of the high pressure consumers is represented by the ordinate f , and the consumption of the low pressure consumers is represented by ordinate g . The last quantity g passes through the motor. At this time, then, the total steam consumption is f plus g which is less than the steam generation e . The difference between the steam generation and the steam consumption is indicated by line h which represents the quantity of steam passing to the accumulator to be stored.

Consideration of the diagram at this time d , therefore, shows that the low pressure consumers need only g steam units and the high pressure consumers f steam units and there is a surplus generation of h steam units. Since the low pressure consumers need only g units there must be some regulation which will prevent the h units of steam from passing into the motor and thence to the low pressure units. The surplus must be taken care of before the steam arrives at the low pressure line, since the connection leading steam to the accumulator is connected to the high pressure conduit and, in such cases, the quantity passing to the low pressure consumers becomes the deciding factor and it becomes evident that in this case the above-mentioned regulation must be controlled by the pressure in the low pressure consumers or conduits connected therewith. In other words, in such a case where there is a greater generation than both high and low pressure consumers will take there must be a regulation which will prevent more than the quantity g from entering the motor and this regulation must be controlled by the condition which controls the amount g , namely the condition in the low pressure conduit.

At another time i , the steam consumption of the high pressure consumers is represented by ordinate k ; the steam consumption of the low pressure consumers is represented by ordinate l , and the steam generation is, as before, equal to the value represented by line a which equals k plus m . At this time the total steam consumption is greater than the steam generation by an amount equal to n . This last value n represents the amount of steam rejected by the accumulator at this time i .

Consideration of the diagram at this time i , therefore, shows that the high pressure consumers need k steam units, and if this amount is supplied thereto there remains but m units to pass through the motor. However the low pressure consumers need l units and therefore there must be a regula-

tion which will prevent more than m units from passing to the motor so that the high pressure consumers may have enough and the low pressure consumers may draw from the accumulator, the discharge of which is connected to the low pressure conduits of the system. In this case, due to the arrangement of the plant, wherein the accumulator discharges into the low pressure conduits, the high pressure consumption becomes the deciding factor and the regulation at this time must be controlled by the pressure in the conduit supplying steam to the high pressure consumers.

The dotted curve o is drawn to coincide with those parts of curves b and c which are uppermost on the figure. This curve represents the controlling values g and m . It is evident that at each time the curve b crosses curve e the regulation is changed. Curve o might be called the regulation curve. Curve o measured downwardly from line a represents the quantity of steam flowing through the motor.

From the above description it will be seen that in the plant of Fig. 1, two devices governed by pressure are needed to control the flow of steam through the motor. One of these devices operates when all the steam for the low pressure consumers passes through the motor, namely when curves e and o coincide. This is indicated on the diagram by the letter r . The other device operates when less steam passes through the motor than is required by the low pressure consumers, namely when the curves b and o coincide. This is indicated on the diagram by the letter s . The first device is to be governed by the pressure behind the motor in accordance with pressure in the conduits connected with the low pressure consumers; the other by the steam pressure before the motor. These devices, operated by the two different pressures, can be combined into one device operated by the two pressures; as will be hereinafter explained.

As seen from the diagram, the steam quantity flowing through the steam motor will vary much less at a plant like this, than if all the steam, not consumed directly from the high pressure line, should pass through the motor as the case is in accumulator plants already known. Hence, a much higher thermo-dynamic efficiency will be obtained in the steam motor.

Figs. 3 to 8 show practical plants arranged with regulating devices governed by the two pressures and will be described in order. In almost all cases it is necessary, beside the two pressure regulations above described, to have a regulation responsive to the speed of the motor. In Fig. 3 the various parts are indicated with the same numerals as in Fig. 2.

The plant shown in Fig. 3 is one wherein

- the turbine delivers power to a circuit E in which all the generated power can be used. In this case the speed regulator and the pressure regulators are all arranged before the turbine in the supply conduit 55. In this figure is shown, diagrammatically, a consumer P, for instance, a group of digesters, connected to the high pressure conduit B. Q is an over-flow valve responsive to the pressure in front of it and functioning to increase its flow area upon increase of pressure and decreasing its flow area upon decrease of pressure. R is a reducing valve responsive to the pressure in the back pressure line of the motor, operating in such a manner that if the pressure in the low pressure conduit drops the valve opens more or less. S is a speed regulator controlling the admission of steam to the motor. As indicated by the fact that the balls of the speed governor are in their lowermost position, the governor is in the nature of a safety device and is normally inoperative, coming into play only if the speed of the motor rises above a value somewhat higher than the normal speed of the motor in which case the speed governor diminishes the amount of steam flowing to the motor and takes over the regulation from the valves Q and R. Governor S, being a control device of "regulating" nature at the higher speed is not like the known "emergency" valve which completely shuts off the steam to a motor at high speed. This latter type of valve may be added to the motor in addition to the regulator S. Normally, the valve controlled by the speed governor is wide open and the steam to the motor is controlled by the two valves Q and R, the one responsive to the pressure in the high pressure conduit and the other responsive to the pressure in the low pressure conduit. Otherwise the various parts are the same as in Fig. 2.
- 45 The operation of the plant shown in Fig. 3 is as follows:
- Suppose there is a surplus of steam generated over the momentary consumption, namely that the plant is working according to the conditions at the time *d* in the diagram of Fig. 1. The valve R then is the regulating means which controls the flow of steam to the turbine. The valve Q is set to open at a somewhat lower pressure than the valve M and so the valve Q at this time will be wide open and the valve M controls the flow of steam to the accumulator and a constant pressure is maintained in the conduit B.
- 60 Suppose now that the steam pressure in the low pressure conduit should drop as a result of more steam being needed by the low pressure consumers. The valve R then opens wider and lets more steam pass through the turbine to the low pressure line.
- 65

If the drop in pressure is so great that the pressure drops in the main conduit due to the fact that the steam consumption has become greater than the steam generation, namely the condition at the time *i* in the diagram of Fig. 1, the valve R will open wide, the valve M will close and the valve Q will throttle down to diminish the supply of steam to the motor. The reducing valve J which is adjusted to open at a lower pressure in conduit G than that at which the valve R opens due to the drop of pressure in the low pressure conduit which allows steam to pass from the accumulator to the low pressure conduit. In this case 75 the valve Q is the device which controls the steam flow through the turbine.

Suppose under these conditions that the pressure in the low pressure conduit rises, as when some of the low pressure consumers 80 are cut out of service. The valve J then closes, the valve R diminishes the flow of steam through the motor, the valve Q opens wide and the valve M opens and regulates the passage of the surplus generated steam 85 over the momentary consumption to the accumulator. This is again the condition at the time *d* and the pressure behind the motor controls the flow of steam therethrough.

If, on the other hand, the variations are in 90 conduit B the plant will operate as follows:

Suppose the pressure in conduit B rises, as when a steam consumer connected to this line is cut out of service. In this event, if valve Q is governing, it will allow more 100 steam to pass through the motor. If now more steam passes through the motor than what is needed in the low pressure consumers, the pressure in conduit G and connection 105 51 rises and valve R closes more or less. As a result, the pressure in conduit B rises and valve M opens whereby the excess of steam passes to the accumulator to be stored.

Suppose the pressure for some reason 110 drops in conduit B, as when more steam is taken to a steam consumer connected to this line. The valve M shuts, first, if it is open, and, after that, if the pressure drops further valve Q starts to shut, letting less steam 115 through the turbine. Thus the pressure drops in conduit G causing valve R to increase its flow area.

However, as the steam flow in this case 120 is limited by valve Q, more steam cannot be taken to the turbine and, consequently, the pressure in the low pressure conduit drops more until valve J opens and the accumulator delivers enough steam to the low pressure conduit to keep its pressure at its 125 predetermined working value.

If the accumulator should be entirely discharged reducing valve O opens letting steam pass from the high pressure conduit 130 to the low pressure consumers.

If the speed of the motor should become excessive, as when all the power generated by the motor is not needed in the electric circuit, the speed regulator S comes into operation and regulates the flow of steam to the motor. In Figure 3 this regulator is shown with hanging arms, which means, that it operates only when the speed of the motor is above a fixed value somewhat higher than the normal speed of the motor, as above mentioned.

Another arrangement is shown in Fig. 4. In this embodiment the overflow valve Q is inserted in the back pressure line 51 but it is, as before, responsive to the pressure in conduit B. Valve R is inserted, as in the arrangement according to Fig. 3 in the conduit before the turbine and is governed by the back pressure. Otherwise the plant is similar to that of Fig. 3.

The operation of this plant is as follows: Suppose the pressure in the low pressure conduit G rises. The flow through valve R then decreases and consequently the pressure in conduit B rises. This rise of pressure in conduit B opens valve Q but this has no effect on the operation since the steam flow through the turbine is at this time regulated by valve R. Consequently opening of valve Q does not lower the pressure in conduit B which rises more, opening valve M thus allowing the surplus steam to pass to the accumulator.

If the pressure in conduit G should decrease for some reason, valve R opens wider and allows more steam to pass to the turbine. In case this opening of valve R should cause a drop of pressure in conduit B, valve Q is actuated to decrease the flow of steam therethrough thereby limiting the steam flow to the low pressure line. This in turn causes a rise of pressure in the back pressure line ahead of valve Q and consequently valve R closes somewhat thereby preventing the pressure in the turbine from rising too high. If now more steam is needed in the low pressure conduit G, valve J opens and the accumulator delivers the steam that is needed.

If, for some reason, the pressure rises in conduit B, the flow through valve Q increases and more steam passes to conduit G. In case the amount thus passing to conduit G is more than is needed by the low pressure consumers the back pressure of the turbine rises and consequently the flow through valve R is correspondingly decreased. Consequently the pressure rises in conduit B until valve M opens enough to allow the excess of steam generated to pass to the accumulator.

If the pressure in conduit B falls the drop of pressure causes valve Q to close somewhat. If, as a consequence, the quantity flowing through valve Q is less than

what is needed by the low pressure consumers, the deficiency will be supplied by the accumulator through valve J. The decrease of flow through valve Q causes a rise of pressure in the turbine exhaust in front of valve Q which, in turn, causes valve R to decrease the flow therethrough in corresponding degree.

Fig. 5 shows a plant in which the function of reducing valve R is taken over by valve M. In this plant an over-flow valve Q is provided, as before, in the conduit in front of the motor, governed by the pressure in the main conduit B and a speed regulator is provided operating as before described.

As pointed out, in connection with the diagram of Fig. 1, in the majority of cases, two regulations are necessary, one governed by the pressure in the high pressure conduit and the other by the pressure in the low pressure conduit. The various devices, as seen from the above disclosure govern, in effect, the relative amounts of steam passing to the motor and to the accumulator. It is possible as shown in Fig. 5 to have the regulation governed by the pressure in the low pressure conduit act directly on the valve controlling the supply to the accumulator. In this arrangement the over-flow valve M is governed by the pressure in the back pressure line in such a way that the valve opens on rise of pressure actuating the same and closes on drop of this pressure.

This plant operates as follows:

Assume at a given time, a certain quantity of steam flows through the motor and a certain quantity through conduit L. Suppose, now, the pressure in conduit B rises. Valve Q then opens wider due to this rise of pressure and more steam flows through the motor. If the consumption of the low pressure consumers does not increase there will be a rise of pressure in conduit G. This rise of pressure causes valve M to open wider allowing the surplus of steam generated to pass to the accumulator. Increase of flow through valve M causes a drop of pressure in conduit B which causes valve Q to close somewhat and thus a new state of balance is obtained wherein a greater amount of steam passes through valve M.

If the pressure in conduit B should drop, under the above assumed conditions, due, for example, to an increase of consumption in the high pressure consumers, the over-flow valve Q then is operated due to the drop of pressure to decrease its flow opening, decreasing the flow of steam to the motor. If, now, less steam passes through the motor than what is needed in the low pressure consumers, the pressure in conduit G drops. This causes valve M to shut partly or entirely. The consequent decrease of flow through valve M causes an increase of flow through valve Q due to changes of pressure

in conduit B. If, despite the increased flow through valve Q and the motor, there is not enough steam in the low pressure conduit the pressure therein drops still further 5 and valve J opens, admitting steam from the accumulator thereto.

Suppose the pressure in the low pressure conduit G rises. Valve M is then operated to allow more steam to pass to the accumulator. Consequently the pressure in conduit 10 B drops and this drop in pressure causes valve Q to decrease its flow opening whereby the pressure in conduit G is reduced.

If, on the other hand, the pressure in conduit G should drop, valve M shuts either 15 partly or entirely and consequently the pressure in conduit B rises causing valve Q to open, increasing the flow through the turbine. If, in this operation, there is a deficiency 20 of steam in the low pressure conduit G despite the increased flow through the motor, valve J opens and the accumulator delivers steam to the low pressure conduit. If the accumulator should, at this moment, 25 be completely discharged valve O in conduit N opens, allowing steam to pass to the low pressure line G.

Figure 6 shows a plant in which an extraction turbine is provided instead of the 30 non-condensing turbines of the previous arrangements. The turbine consists in a high pressure section T and a low pressure section U. The exhaust of the low pressure section is directly connected to a condenser V. Between the two sections of the turbine a valve 35 50 is arranged in the connection 52 controlled by a speed governor X to regulate the steam flow to the low pressure section of the turbine.

40 An extraction connection or bleed line 51, corresponding to the back pressure line 51 of the previous arrangements connects the steam communication 52 between the two sections of the turbine with conduit G at a 45 point in the steam communication 52 ahead of the valve 50.

In this case the exact amount of power 50 needed in the electric circuit E will be generated by the turbine, differing in this respect from the previous arrangements where all the power generated by the turbine could be used in the circuit. If the steam passing from the high pressure section to the low pressure section is not sufficient 55 for the power demanded, steam will flow from the accumulator through valve J; connection 51, valve 50 and communication 52, to the low pressure section. This is very important where the consumption varies greatly. Valves Q and R are similar 60 in construction and function to those of Fig. 3.

With the above explanation the operation of the plant will be easily understood by

reference to the description of operation 65 of Fig. 3.

The valves Q and R can be arranged in the same way as in Figs. 4 and 5 and the operation of the plant will be similar to that described with reference to those 70 figures.

This is apparent upon consideration that the pressure in conduit G and connection 75 51 is the same and that therefore the low pressure section may be considered as a distinct consumer fed with steam from the low pressure conduit G, and governed by a centrifugal governor in normal manner. Thus the plant is like that of Fig. 3 except for the addition of a speed governed motor supplied from conduit G. Now just as Fig. 80 4 was evolved from Fig. 3 by moving overflow valve Q to the back pressure connection 51 but, however, retaining its control as responsive to the pressure in conduit B, so an arrangement may be made according to Fig. 6 except that overflow valve Q is placed 85 in extraction connection 51 but is governed by the pressure in conduit B. The operation will then be the same as that of Fig. 4 except for the influence of the speed governed consumer; that is, the low pressure section of the turbine. It is to be 90 observed, however, that if valve Q is placed 95 in connection 51 at a point between its jointure with communication 52 and the low pressure conduit G that the plant must be one wherein the steam consumption of the motor does not exceed the steam production of the steam boilers at any time since the low pressure section can then not take steam from the accumulator. If, however, the valve Q is placed close up to the motor before the jointure of connection 51 with communication 52, the low pressure section 100 can take steam from the accumulator and thus the motor may at times consume more steam than is generated.

Furthermore, as the plant according to Fig. 5 was evolved from Fig. 3 by omitting valve R and changing the regulation of valve M so that it is responsive to the pressure previously controlling valve R, so an arrangement can be made according to Fig. 6 except that the regulation of valve M is 110 changed to responsiveness to the pressure in connection 51 and valve R removed. The operation will then be the same as that of Fig. 5 except for the influence of the 115 low pressure section of the turbine.

As is obvious, in practice the turbine sections would in most probability be united into one casing, which casing would also include valve 50 controlling the flow of steam 120 to the low pressure wheels.

The showing of the turbine and the speed regulators is obviously merely diagrammatic and may have many forms in prac-

5 tice. The speed regulation may include any mechanism which will first regulate the steam flow to the low pressure section, and, when this is completely shut off, reduce the steam flow to the high pressure section. Such mechanisms are well known.

10 Fig. 7 illustrates a plant embodying an extraction turbine in which the pressure operated valves connected with motor lines are arranged in a different manner than previously described.

15 In this construction an over-flow valve Z is inserted in the communication 52. This valve Z is regulated by the extraction pressure in connection 51 in such a way that it increases the flow of steam to the low pressure section if the extraction pressure increases and decreases the flow of steam therethrough if the extraction pressure decreases. Valve Q is inserted in the extraction connection 51 between conduit G and the point at which connection 51 is connected to connection 52. This valve is regulated as before by the pressure in conduit 20 B.

25 Speed regulator S regulates the flow of steam to the high pressure section and is normally in operative action, as is shown by the outward position of the balls of the governor. Speed regulator X is normally inactive as is shown by the drooping position of the arms of the governor and comes into operation only if the speed for some reason should rise above its normal value.

30 The plant shown in Fig. 7 operates as follows:

35 Suppose the pressure in the low pressure conduit G rises due to decreased consumption of low pressure consumers H. This causes the pressure in connection 51 to rise which actuates valve Z to increase its flow area and cause more steam to pass to the low pressure section U of the turbine. The speed of the turbine consequently increases and speed regulator S cuts down the flow of steam to the high pressure section. This causes a rise of pressure in conduit B. This rise of pressure in conduit B causes opening of valve Q but this has no effect as the steam flow to the motor is determined by speed regulator S and valve Z. The result, then, of the rise of pressure in conduit B is to cause valve M to increase the amount of steam passing through conduit M to the accumulator.

40 Suppose the pressure in conduit G decreases. The resulting drop of pressure in conduit 51 causes valve Z to decrease its flow area, decreasing the flow of steam to the low pressure section U. Consequently more steam passes to the low pressure conduit G. Assuming the load on the motor is unchanged, the revolutions of the motor decrease due to the decreased flow of steam

45 to the low pressure section U and speed regulator S causes more steam to pass to the high pressure section of the turbine, which section now takes over the load taken from the low pressure section when valve Z decreased the steam flow thereto. Thus the 50 deficiency in the low pressure conduit is made up partly by cutting off the flow to the low pressure section and partly by increasing the flow through the high pressure section. If under these conditions the demand for steam in the low pressure conduit is greater than what can be supplied through the bleed connection 51, the pressure in conduit G drops further and valve 55 J is caused to open so that steam is delivered to the low pressure conduit from the accumulator conduit K.

60 If the pressure in conduit B should drop too much when speed regulator S increases the flow to the high pressure section, valve 65 Q closes somewhat, cutting off a corresponding quantity of steam from the low pressure conduit. In this event, a decrease in pressure in the low pressure conduits causes valve J to open.

65 Suppose the pressure in conduit B rises for some reason. This rise in pressure causes valve Q to increase its flow area and more steam passes to the low pressure conduit. If the consumption in the low pressure consumers has not increased in corresponding degree, the pressure in the conduit G will rise. As a result valve Z will be 70 opened wider, permitting more steam to flow to the low pressure section. This causes an increase of the turbine speed and speed regulator S causes the flow of steam to the high pressure section to be decreased which, in turn, causes the pressure in conduit B to increase and this increase of pressure 75 actuates valve M to open the same and allow the surplus to flow to the accumulator F.

80 Suppose the pressure in conduit B drops. If valve M is open, it then closes partially or entirely. After valve M has closed completely valve Q is actuated to decrease the flow of steam through it and less steam passes through the turbine to the low pressure conduit. This causes a rise in pressure 85 in connection 51 before the valve Q and this rise in pressure causes valve Z to increase the flow of steam to the low pressure section of the turbine. This increases the number of revolutions of the turbine and consequently speed regulator S cuts off a part of the steam passing to the high pressure section of the turbine.

90 This causes the pressure in conduit B to rise again and the deficiency of steam in the low pressure consumers is supplied by the accumulator F through valve J. If the accumulator should happen to be discharged,

valve O opens to allow steam to pass from the boilers to the low pressure consumers.

Fig. 8 shows a plant provided with a double extraction turbine. In this plant there is a steam line B₁ to which the steam consumers P₁ are connected. Further, two valves M₁ and O₁ are put in between conduit B₁ and accumulator conduit K. These valves are governed analogously to valves M and O. The turbine has three sections Y, T and U, the last of which exhausts into condenser V.

Valve Q in communication 53 between the high and intermediate sections of the turbine is an overflow valve actuated by the pressure in the bleed line from the high pressure section.

Valve R in this same connection is a reducing valve actuated by the pressure in extraction conduit 54 bleeding steam from the intermediate section.

Over-flow valve Q₁ is responsive to pressure in the main conduit B and operates as the other over-flow valves herein before explained.

Both the speed regulator S in front of the high pressure section and the speed regulator S₁ between the high pressure and intermediate pressure sections operate only when the number of revolutions of the turbine is higher than normal value. The speed regulator X regulates the steam quantity to the low pressure section of the turbine and is in active regulation at the normal number of revolutions of the turbine.

If the high pressure section of the turbine and the high pressure conduits were omitted so that the boilers delivered steam directly to conduit B₁, the construction would be the same as that of Fig. 6. For this reason it is unnecessary to go into a description of Fig. 8. It is only necessary to point out that variations in conduits B are transferred to conduit B₁, this being accomplished by the operation of valves M, Q₁ and O. The regulating devices for plants having double extraction turbines can be arranged as disclosed in connection with Figs. 6 and 7. It is easily seen that sections T and U are exactly analogous to sections T and U in these figures referred to.

To make the operation of the various regulating arrangements herein before described clear the description has been developed on the basis that each impulse, such as a pressure impulse or a speed impulse acts on a separate valve. The valves controlling the flow of steam to the motor are placed in series in the steam path of the motor. For example, in Fig. 6 there are three valves, Q, R and the valve controlled by speed governor S in series in the supply conduit 55. The reason that they can be placed in one conduit in series is that the operation, as will

have been noticed by the preceding description, is such that the valve which is most closed is the controlling valve; that each separate impulse derived from any one of the governing conditions is able to shut off the steam through the motor or a part thereof and thus the desired result is obtained. The series connection is characterized by this condition that any impulse can decrease the flow of steam through the power unit independently of the tendency of any of the other impulses to increase the flow there-through.

However an arrangement involving several valves placed one after the other always causes considerable drop in pressure in the medium passing through them; in this case steam. Hence it is often preferable to have the impulses act on a single controlling member, which regulates the steam flow to the motor. Fig. 9 shows a construction wherein this is accomplished.

In Fig. 9, 3 represents a conduit through which steam flows. This may be the supply conduit 55 of the previous figures. 2 is the valve in the conduit which is to be controlled by a plurality of impulses such as pressure and speed. 4 is a liquid pressure operated servo-motor, the piston 5 of which is connected by means of a stem with the valve member 6. The pressure liquid operating the servo-motor is controlled by slide valve 7 which operates to allow the pressure liquid to pass to and from the servo-motor in a manner shown by the arrows. Slide valve 7 is connected to arm 11 by means of lever 8 and rods 9 and 10. The position of arm 11 controls the position of slide valve 7 and thus controls the supply of liquid to and return from the servo-motor. Arm 11 is acted upon by a spring 12 which tends to move the arm upwardly. Acting on the arm are two pressure operated mechanisms. These mechanisms represent in part the over-flow and reducing valves of the previous figures.

The pressures operate on the two pistons 13 and 14 which are acted upon by springs 15 and 16. The spring 15 acts on the upper side of piston 13; spring 16 acts on the lower side of piston 14. The arrangement is such that the pressure impulse which closes the valve partly or entirely upon a rise of pressure, namely the reducing impulse, operates the piston 14 while the pressure which opens the valve more or less upon a rise of pressure, namely the over-flow impulse, operates piston 13. If, for instance, the arrangement should be applied to the plant shown in Fig. 3, the piston 14 and associated parts correspond to the actuating mechanism for valve R and the piston 13 and associated parts correspond to the actuating mechanism for valve Q. The piston rods 17 and 18 are hollow and in them are arranged slidable pins

19 and 20. Two springs 21 and 22 form resilient connections between the piston rods 17 and 18 and the slideable pins 19 and 20 respectively so that, under certain conditions, by compressing the said springs, the piston rods and the pins may have relative movement.

As shown in this figure, a speed governor S may be arranged to actuate the arm 11. 10 This is accomplished by means of the rod 24 operated by means of lever 23. As is shown the rod 24 extends loosely through the arm 11 and is provided with two stops 25 and 26 one on each side of the arm 11 arranged so that there is a certain amount of play between the arm and the stops. The arrangement operates in the following manner:

If the pressure above the piston 14 for any 20 reason rises, this piston with its rod 18 is moved downwardly and as the spring 22 is stronger than the spring 12 the arm 11 is also pressed downwardly as soon as the lost motion between pin 20 and piston rod 18 is overcome. The downward movement of arm 11 causes slide valve 7 also to be moved downwardly and the pressure fluid then enters the servo-motor on the upper side of piston 5 and the lower side of piston 5 is connected with the out-flow. Thus the piston 5 is moved downwardly and the main valve 2 is closed more or less. The arrangement including the lever 8 operates to return slide valve 7 to its middle position in well known manner.

Suppose on the contrary that the pressure acting on piston 14 falls. This causes arm 11 to be moved upwardly by aid of the spring 12, provided no other impulse is acting to press the arm downwardly. Now if the arm is moved upwardly the slide valve 7 will also move upwardly and the pressure liquid will pass to the lower side of piston 5 in the servo-motor causing the valve to open more or less.

Suppose the pressure acting on piston 13 should rise, this piston will then be moved upwardly compressing the spring 15 and the arm 11 can be moved upwardly by the spring 12, provided no other impulse tends to move the arm downwardly. As explained, this movement of the arm will cause the valve to open. If, on the other hand, the pressure acting below piston 13 should drop, this piston will be moved downwardly by spring 15. In this case, at first, the lost motion which may occur between rod 17 and pin 19 will be overcome and then arm 11 will be moved downwardly and the valve will be closed, either partially or entirely.

If, despite the action of the pressure regulators, too much steam flows through the conduit 3, thereby causing too much steam to pass to the motor, so that the motor speeds

up beyond its normal limit, the speed regulator S will operate to move rod 24 downwardly whereby the stop 25 will move arm 11 downwardly and will cause the valve to decrease its flow area thus decreasing the supply of steam therethrough. Consequently, in this case the speed regulator takes care of the regulation regardless of the effect of the pressure operated elements. If, owing to the influence of a pressure impulse, too small a quantity of steam should be supplied to the motor, the speed of the latter will decrease and when attaining the lowest permissible limit, the speed regulator will again control the regulation by causing the stop 26 to bear against arm 11 which will increase the flow of steam through the valve. If, at this time, either of the pressure impulses tends to shut the valve, the springs 21 or 22 will be compressed and the effect of these impulses will be eliminated.

It is obvious that in place of pistons 13 and 14 equivalent devices may be used, such as diaphragms or bellows.

It will be readily seen that it is not necessary to insert a valve 2 in the conduit supplying steam to the motor if the motor is such that it is already provided with admission controlling valves arranged in the motor itself. In such cases it is within the scope of this invention that the impulses be arranged to act on the existing governing devices of the motor.

What we claim as new and desire to secure by Letters Patent of the United States of America is:—

1. In a steam plant, in combination, a steam generator, a motor, means to conduct steam from said generator to said motor, a low pressure conduit, an accumulator, an accumulator conduit connected therewith, a reducing valve receiving steam from said accumulator conduit and delivering the same to said low pressure conduit, means to conduct steam from said generator parallel to said motor to said accumulator, means to conduct steam from said motor to said low pressure conduit and a consumer connected to receive steam from said low pressure conduit.

2. A steam plant comprising in combination a steam generator, a steam motor, an accumulator, a consumer, means to pass steam from said generator to said motor, means to pass steam from said generator to said accumulator, a conduit adapted to lead steam from said accumulator to said consumer, a member in said conduit responsive to the pressure behind the same to control the flow of steam therethrough, a connection between said motor and said conduit, said connection being connected to said conduit at a point behind said member.

3. A steam plant comprising in combina-

- tion a steam generator, a steam motor adapted to receive steam from said generator, a steam accumulator, a conduit leading steam from said generator toward said accumulator, means in said conduit responsive to the pressure in front of the same to control the flow of steam therethrough and adapted to allow flow of steam upon an increase of said pressure above a predetermined value, a consumer, a conduit connecting said accumulator with said consumer, a member in said last-mentioned conduit responsive to the pressure behind the same and operating to control the flow of steam therethrough, a connection adapted to receive steam from said motor and to deliver steam to said last-mentioned conduit at a point between said member and said consumer.
4. In a steam plant, in combination, a steam generator, a consumer, two parallel paths for the passage of steam from said generator to said consumer, the one path containing an over-flow valve and a reducing valve, and having an accumulator connected therewith between said over-flow valve and said reducing valve, and a steam motor in the other path.
5. In a steam plant, the combination with a source of steam, a motor and an accumulator supplied from said source, a consumer supplied both from the motor and the accumulator of automatic means to control flow of steam from the accumulator to the consumer responsive to variations of pressure in the steam supplied from the motor.
6. A steam plant comprising in combination a steam generator, a steam conduit system connected therewith, a steam motor in said conduit system, an accumulator in said conduit system, a consumer in said conduit system, a connection delivering steam from said motor toward said consumer, means to maintain a lower pressure in said connection than in said accumulator, and means to control the steam flow to said motor responsive to the pressure in front of said motor and responsive to the pressure in said connection.
7. A steam plant comprising in combination a steam generator, a steam conduit system connected therewith, an extraction motor, an accumulator and a steam consumer in said conduit system, means to withdraw steam from said motor and supply the same to said consumer, means to supply steam from said accumulator to said consumer, means to maintain the extraction pressure always lower than the pressure in said accumulator, means operative at the normal speed of the motor to control the steam flow to said motor responsive to variations of pressure in steam supplied to said motor and variations of pressure in steam withdrawn from said motor, and means responsive to the speed of the motor operating at a value of speed somewhat higher than the normal speed of the motor to nullify the effect of the pressure responsive means, and to control the flow of steam to said motor.
8. In a steam plant, in combination, a steam generator, a consumer, two parallel paths for flow of steam from said generator toward said consumer, the one path containing an over-flow valve and a reducing valve, and having an accumulator connected therewith between said over-flow valve and said reducing valve, means to convert the energy of steam into kinetic energy in the other path and mechanism to regulate said means responsive to the pressure before and behind said means.
9. A steam-plant as set out in claim 6 wherein the means to control the flow of steam to the motor, besides being responsive to pressure, also includes mechanism responsive to the speed of the motor.
10. A steam plant comprising in combination a steam generator, a steam motor adapted to receive steam from said generator, a steam accumulator, a conduit leading steam from said generator toward said accumulator, means in said conduit responsive to the pressure in front of the same to control the flow of steam through said conduit toward said accumulator and adapted to allow flow of steam upon an increase of said pressure above a predetermined value, a supply conduit leading steam to said motor and a connection leading steam from said motor, means to control the steam flow to said motor responsive to the pressure in said supply conduit and the pressure in said connection, a consumer, a conduit connecting said accumulator with said consumer, a member in said last mentioned conduit responsive to the pressure behind the same and operating to control the flow of steam therethrough, and means whereby the said connection leading steam from the motor leads steam into said last mentioned conduit at a point between said member and said consumer.
11. In a steam plant, in combination, a steam generator, a consumer, two parallel paths for passage of steam from said generator toward said consumer, the one path containing an over-flow valve and a reducing valve and having an accumulator connected therewith between said over-flow valve and said reducing valve, means to convert the energy of steam into kinetic energy in the other path and mechanism to regulate said means responsive to the pressure before and behind said means and responsive to the energy produced by said means.
12. In a steam plant, in combination, a steam generator, a high pressure conduit connected therewith, a conduit of lower

- pressure, a connecting conduit for passage of steam from said high pressure conduit to said conduit of lower pressure, a valve in said connecting conduit responsive to the pressure in front of the same and operating to increase its flow opening upon an increase of the actuating pressure and decrease its flow opening upon a decrease of the actuating pressure, an accumulator connected with said conduit of lower pressure and adapted to receive steam passing through said connecting conduit, a reducing valve in said conduit of lower pressure, a motor adapted to receive steam from said high pressure conduit, a connection leading steam from said motor to said conduit of lower pressure at a point behind said reducing valve, means to control the steam flow to said motor responsive to the pressure in front thereof, responsive to the pressure in said connection and responsive to the speed of the motor and a steam consumer connected to said conduit of lower pressure at a point behind said reducing valve.
13. A steam plant as set out in claim 6 wherein the means to control the steam flow to the motor comprises a plurality of mechanisms arranged ahead of said steam motor, one of which mechanisms is responsive to the pressure of steam supplied to the motor and another of said mechanisms to the pressure of steam in the connection delivering steam from the motor toward the consumer.
14. In a steam plant, in combination, a steam generator, a high pressure conduit, an accumulator, an accumulator conduit connected therewith, a connecting conduit for passage of steam from said high pressure conduit to said accumulator conduit, a valve in said connecting conduit responsive to the pressure in front of the same and operating to increase the flow of steam therethrough when said pressure increases and to decrease the flow of steam therethrough when the pressure decreases, a low pressure conduit, a consumer connected with said low pressure conduit and adapted to receive steam therefrom, means to pass steam from the accumulator conduit to the low pressure conduit operated by the pressure in the low pressure conduit, a motor composed of several sections including a high pressure section, a supply conduit connecting said high pressure conduit with said high pressure section to supply steam thereto, a connection leading steam from said high pressure section to said low pressure conduit and means to control the flow of steam to said high pressure section.
15. In a steam plant, in combination, a steam generator, a high pressure conduit, an accumulator, an accumulator conduit connected therewith, a connecting conduit for passage of steam from said high pressure
- conduit to said accumulator conduit, a valve in said connecting conduit responsive to the pressure in front of the same and operating to increase the flow of steam therethrough when said pressure increases and to decrease the flow of steam therethrough when the pressure decreases, a low pressure conduit, a consumer connected with said low pressure conduit and adapted to receive steam therefrom, means to pass steam from the accumulator conduit to the low pressure conduit operated by the pressure in the low pressure conduit, a motor composed of several sections including a high pressure section, a supply conduit connecting said high pressure conduit with said high pressure section to supply steam thereto, a connection leading steam from said high pressure section to said low pressure conduit and means to control the flow of steam to said high pressure section, a low pressure conduit to said low pressure conduit, a motor composed of several sections including a high pressure section and a low pressure section, a supply conduit connecting said high pressure conduit with said high pressure section, a connection leading steam from said high pressure section to said low pressure conduit, a steam communication between said high and low pressure sections, speed responsive means to control the flow of steam through said communication and pressure responsive means to control the flow of steam through said high pressure section.
16. In a steam plant, in combination, a steam generator, a high pressure conduit, an accumulator, an accumulator conduit connected therewith, a connecting conduit for passage of steam from said high pressure conduit to said accumulator conduit, a valve in said connecting conduit responsive to the pressure in front of the same and operating to increase the flow of steam therethrough when said pressure increases and to decrease the flow of steam therethrough when the pressure decreases, a low pressure conduit, a consumer connected with said low pressure conduit and adapted to receive steam therefrom, means to pass steam from the accumulator conduit to the low pressure conduit operated by the pressure in the low pressure conduit, a motor composed of several sections including a high pressure section and a low pressure section, a supply conduit connecting said high pressure conduit with said high pressure section, a connection leading steam from said high pressure section to said low pressure conduit, a steam communication between said high and low pressure sections, speed responsive means to control the flow of steam through said communication and pressure responsive means to control the flow of steam through said high pressure section.
17. In a steam plant, in combination, a steam generator, a high pressure conduit, an accumulator, an accumulator conduit connected therewith, a connecting conduit for passage of steam from said high pressure conduit to said accumulator conduit, a valve in said connecting conduit responsive to the pressure in front of the same and operating to increase the flow of steam therethrough when said pressure increases and to decrease the flow of steam therethrough when the pressure decreases, a low pressure conduit,

- 5 a consumer connected with said low pressure conduit and adapted to receive steam therefrom, means to pass steam from the accumulator conduit to the low pressure conduit 65
5 operated by the pressure in the low pressure conduit, a motor composed of several sections including a high pressure section and a low pressure section, a supply conduit connecting said high pressure conduit with 70
10 said high pressure section, a connection leading steam from said high pressure section to said low pressure conduit, a steam communication between said high and low pressure sections, a valve in said steam communication, speed responsive means to control said valve, means to control the flow of steam through said high pressure section 75
15 responsive to the pressure in said supply conduit and in said connection. 80
20 18. In a steam plant, in combination, a steam generator, a high pressure conduit, an accumulator, an accumulator conduit connected therewith, a connecting conduit for the passage of steam from said high pressure conduit to said accumulator conduit, a valve in said connecting conduit responsive to the pressure in front of the same and operating to increase the flow of steam therethrough when said pressure increases and to 85
25 decrease the flow of steam therethrough when the pressure decreases, a low pressure conduit, a consumer connected with said low pressure conduit and adapted to receive steam therefrom, means to pass steam from the accumulator conduit to the low pressure conduit operated by the pressure in the low pressure conduit, a motor including a low pressure section and a section of higher pressure, a supply conduit connecting said high pressure conduit with 90
30 said motor to supply steam thereto, a steam communication leading steam from said section of higher pressure to said low pressure section, a valve in said communication, a speed responsive device to control said valve operating during normal speed of the motor, a connection leading from a point in said communication ahead of said valve to said low pressure conduit, means responsive to the pressure in said connection to control the flow of steam through said section of higher pressure and other means to control the flow of steam through said section of higher pressure responsive to the pressure in a conduit 95
35 carrying a pressure higher than said connection. 100
40 19. In a steam plant, in combination, a steam generator, a high pressure conduit, an accumulator, an accumulator conduit connected therewith, a connecting conduit for passage of steam from said high pressure conduit to said accumulator conduit, a valve in said connecting conduit responsive to the pressure in front of the same and operating to increase the flow of steam therethrough when said pressure increases and to decrease 105
45 the flow of steam therethrough when the pressure decreases, a low pressure conduit, a consumer connected with said low pressure conduit and adapted to receive steam therefrom, means to pass steam from the accumulator conduit to the low pressure conduit operated by the pressure in the low pressure conduit, a motor composed of several sections including a low pressure section, a supply conduit connecting said high pressure 110
50 conduit with said motor, means to control the steam passing to said low pressure section, a connection leading from said motor at a point ahead of the last mentioned means to said low pressure conduit and means to control the supply of steam to said motor. 115
55 20. In a steam plant, in combination, a steam generator, a high pressure conduit, an accumulator, an accumulator conduit connected therewith, a reducing valve receiving steam from said accumulator conduit and delivering the same to said low pressure conduit, means to conduct steam from said generator parallel to said consumer to said accumulator, means to conduct steam from said consumer to said low pressure conduit and a second consumer connected to said low pressure 120
60 conduit. 125
65 21. In a steam plant in combination, a steam generator, a consumer, means to conduct steam from said generator to said consumer, a low pressure conduit, an accumulator, an accumulator conduit connected therewith, a reducing valve receiving steam from said accumulator conduit and delivering the same to said low pressure conduit, means to conduct steam from said generator parallel to said consumer to said accumulator, means to conduct steam from said consumer to said low pressure conduit and a second consumer connected to said low pressure conduit.
- 70 22. In a steam plant, in combination, a steam generator, a condensing extraction consumer, means to conduct steam from said generator to said consumer, a low pressure

conduit, an accumulator, an accumulator conduit connected therewith, a reducing valve receiving steam from said accumulator conduit and delivering the same to said low pressure conduit, means to conduct steam from said generator parallel to said condensing extraction consumer to said accu-

mulator, means to extract steam from said condensing extraction consumer and deliver the same to said low pressure conduit, and a consumer connected to said low pressure conduit.
